A. BYRON

Des. 159,137

APRON OR SIMILAR ARTICLE

Filed June 15, 1949

Inventor
Andrea Byron

by The Firm of Charlesworths Atlys

UNITED STATES PATENT OFFICE

159,137

APRON OR SIMILAR ARTICLE

Andrea Byron, Oakland, Calif., assignor to Robert R. Lokey, Jr., and Arthur W. Bromfield, both of Los Angeles, Calif.

Application June 15, 1949, Serial No. 3,289

Term of patent 7 years

(Cl. D3—26)

To all whom it may concern:

Be it known that I, Andrea Byron, a citizen of the United States and a resident of the city of Oakland, in the county of Alameda and State of California, have invented a new, original, and ornamental Design for an Apron or Similar Article, of which the following is a specification, reference being had to the accompanying drawing, forming a part thereof.

On the drawing, the figure is a plan view of the apron or similar article, showing my new design.

I claim:

The ornamental design for an apron or similar article, as shown.

ANDREA BYRON.
